(57) **CLAIM**

The ornamental design for a handheld communication device, as shown and described.

DESCRIPTION

FIG. 1 is a front perspective view of a first embodiment of a handheld communication device, showing our new design; FIG. 2 is a rear perspective view of the first embodiment thereof;

FIG. 3 is a front view of the first embodiment thereof; FIG. 4 is a rear view of the first embodiment thereof; FIG. 5 is a first side view of the first embodiment thereof; FIG. 6 is a second side view of the first embodiment thereof; FIG. 7 is a top view of the first embodiment thereof; and FIG. 8 is a bottom view of the first embodiment thereof.

FIG. 9 is a front view of the handheld communication device of FIG. 1 showing the illuminated region in an illuminated state;

FIG. 10 is a front perspective view of a second embodiment of a handheld communication device, showing our new design;

FIG. 11 is a rear perspective view of the second embodiment thereof;

FIG. 12 is a front view of the second embodiment thereof; FIG. 13 is a rear view of the second embodiment thereof; FIG. 14 is a first side view of the second embodiment thereof;

FIG. 15 is a second side view of the second embodiment thereof;

FIG. 16 is a top view of the second embodiment thereof; and FIG. 17 is a bottom view of the second embodiment thereof.

FIG. 18 is a front view of the handheld communication device of FIG. 10 showing the illuminated region in an illuminated state;

FIG. 19 is a front perspective view of a third embodiment of a handheld communication device, showing our new design; FIG. 20 is a rear perspective view of the third embodiment thereof;

FIG. 21 is a front view of the third embodiment thereof;

FIG. 22 is a rear view of the third embodiment thereof;

(Continued)

FIG. 23 is a first side view of the third embodiment thereof; FIG. 24 is a second side view of the third embodiment thereof;

FIG. 25 is a top view of the third embodiment thereof; and FIG. 26 is a bottom view of the third embodiment thereof.

FIG. 27 is a front view of the handheld communication device of FIG. 19 showing the illuminated region in an illuminated state;

FIG. 28 is a front perspective view of a fourth embodiment of a handheld communication device, showing our new design;

FIG. 29 is a rear perspective view of the fourth embodiment thereof;

FIG. 30 is a front view of the fourth embodiment thereof;

FIG. 31 is a rear view of the fourth embodiment thereof;

FIG. 32 is a first side view of the fourth embodiment thereof;

FIG. 33 is a second side view of the fourth embodiment thereof;

FIG. 34 is a top view of the fourth embodiment thereof; and FIG. 35 is a bottom view of the fourth embodiment thereof, and,

FIG. 36 is a front view of the handheld communication device of FIG. 28 showing the illuminated region in an illuminated state.

The broken lines shown in FIGS. 10-18 and FIGS. 28-36, that are immediately adjacent to the shaded areas, and define the unshaded regions, show portions of the handheld communication device that form no part of the claimed design of the second and fourth embodiments. The broken line shape

having broken lines radiating in FIGS. 9, 18, 27, and 36, show the illuminated region in an operation of use and form no part of the claimed design.
